WRINGER MOP

John L. Nilson, Chicago, Ill.

Application May 17, 1935, Serial No. 22,084

8 Claims. (Cl. 15—120)

My invention relates to the twist wringing type of mop in which I provide a compensating spring actuated torque arm structure and a selector ratchet mechanism in which the pawl rather than the ratchet is the rotor so that the pawl, which is nearest the operator's fingers is more accessible for operation.

Among the objects of my invention is to provide a structure wherein the wringing mechanism when released from closed position springs upwardly toward the hand of a user, and remains there during the wringing operation;

To create a structure wherein the force is greater toward the open position of the wringing mechanism (which is the point of greatest use) than it is toward the closed position thereof where spring force is not desired, so as to, therefore, give greater ease to the user in closing the wringing mechanism;

To create a compensating spring actuated torque arm structure to counteract the combined weight of the movable parts of the wringer mop;

To provide a selector in combination with a ratchet mechanism whereby the operator with his finger tips may at any time control the engagement or release of the pawl. Heretofore in ratchet mechanism it has been necessary for the operator to both relieve the tension on the pawl simultaneously with disengaging the pawl, a task that was extremely difficult, if not impossible for the average operator. With my invention the selector automatically disengages the pawl so that the operator need only direct his efforts and attention toward relieving the tension of the pawl by the same directional movement of the handle of the wringing mechanism;

To create a ratchet mechanism in wringer mops in which the working parts are not exposed to physical destruction or cause injury to person or property by contact therewith;

To supply a locking means for holding the wringing mechanism in closed position to the handle of my wringer mop;

And such other objects, advantages and capabilities as will later more fully appear and which are inherently possessed by my invention.

While I have shown in the accompanying drawings preferred embodiments of my invention yet I wish it understood that the same are susceptible of modification and change without departing from the spirit of my invention.

Referring more particularly to the drawings: Fig. 1 is a front elevational view of my device; Fig. 2 is a side elevational view in wringing position; Fig. 3 is a side elevational view in closed or

mopping position; Fig. 4 is an enlarged detail of my ratchet member in combination with the selector; Fig. 5 is a similar view to Fig. 4 showing the selector in raised position so that the pawl is in engagement with the teeth of the ratchet plate; Fig. 6 is a plan sectional view on line 6—6 of Fig. 4; Fig. 7 is a perspective view of the selector; Fig. 8 is a perspective view of the revolving reciprocating pawl.

My wringer mop comprises a handle 10, a compensating spring actuated torque arm structure 11, a wringing mechanism 12, a swab holder 13 connected to the bottom of the handle 10 and a swab 14 extending between the swab holder 13 and the wringing mechanism 12.

Referring more particularly to my compensating spring actuated torque arm structure 11, it comprises a torque arm 15 pivotally mounted at 20 through the handle 10 and bent at 16 substantially at right angles and transverse to the axis 20 of the handle to form a bearing 16 for a U shaped member 17 of the wringing mechanism 12. A push rod 18 is slidably and pivotally mounted through a center pin 19 in the handle 10. Said center pin 19 is pivotally mounted through the handle 10 and is offset from the pivot point 20 of the torque arm 15. The other end of the push rod 18 is pivotally mounted to the end of the bent-over portion 16 of the torque arm 15 to form a stop 21 for the U shaped member 17 of the wringing mechanism 12. The push rod 18 on one end slides through center pin 19. A spring 22 is mounted on said push rod 18 and is interposed between center pin 19 and a stop member 23 on push rod 18 so that as the push rod 18 is carried downwardly toward the closed position of the wringer mop the spring compresses between the center pin 19 and the stop member 23 until the approximate dead center of the pivot centers is reached where the effect of the spring action is neutralized and vice versa, so that the spring force is most effective when the wringer mop is in open wringing position.

Referring more particularly to the wringing mechanism 12, I employ a U shaped member 17 which is supported on the bearing 16 of the torque arm 15 and also acts as a bearing for the twisting shaft 24, which passes transversely through the U shaped member 17 in such a way as to hold the assembly in place. A ratchet plate 25 is attached to the U shaped member 17 by dogs, lugs or the like 26 and follows the movement of the U shaped member 17 when the U shaped member pivots on the torque arm 15. The ratchet plate 25 has a plurality of recesses 55

27 adapted to be engaged by a reciprocating revolving pawl 28. In addition I employ a selector 29 having a finger control 30 slidably mounted on the twisting shaft 24 and having a bar 31 continuing downwardly to receive a flat spring 32 which actuates the pawl 28 depending upon the location of the selector 29. As the selector 29 is pushed downwardly the spring 32 actuates the pawl 28 and as it is pushed upwardly it disengages the pawl 28 from contact with the ratchet plate 25. The pawl 28 is pivoted and supported by both sides 33 and 34 of a casing 35 which is a substantially U shaped member and functions to protect the mechanism which it covers. A bent portion 36 of the twisting shaft 24 acts as a driving dog for carrying the casing with the shaft as the shaft is twisted. The U shaped casing 35 is held closed and in fixed position on the twisting shaft 24 by two rivets 37 and 38, both of said rivets passing through said casing and one rivet 37 placed in substantially the center of the cavity formed by the bent portion 36 of the twisting shaft 24 and the other rivet 38 placed on the opposite side of the twisting shaft 24 somewhat closer to the upper end of the casing 35 in cooperation with the hole 39 formed in the bottom part of the U shaped casing 35 where the twisting shaft passes through forming a three point contact. This structure 30 is particularly designed to obviate the necessity of any direct connection through the twisting shaft and thus prevents the weakening of the same. A stop member 41 is mounted on the twisting shaft 24 below said U shaped member 17 for retaining said U shaped member 17 against the ratchet plate 25, and the ratchet plate 25 in turn against the casing 35.

When my wringer mop is in closed position for operation the torque arm 15 and the push rod 18 lie substantially parallel on the handle 10. Likewise the wringing mechanism 12 with the twisting shaft 24 and an extension therefrom forming a handle 40 lie on top of the torque arm 15, the handle 10 and the push rod 18. In order to hold these parts in fixed position I insert a hook member 41 in the handle 10 and pivoted to the same at such a position that the hook member 41 when moved downwardly by gravity engages the handle 40 of the twisting shaft 24 and holds the entire structure in closed fixed position.

Having thus described my invention I claim:

1. A wringer mop comprising an elongated handle, a swab, means for holding the swab at one end adjacent the end of said handle, a torque arm pivoted transversely to said handle to swing toward and away from said handle, a retaining rod pivotally connected at its outer end to the outer end of said torque arm, and at its inner end slidably and pivotally mounted to said elongated handle at a point offset from the pivot point of said torque arm for holding the wringer mop in wringing position, a U shaped member, said torque arm having a bent over portion substantially at a right angle and transverse to the axis of said handle, said bent over portion lying within the closed end of and forming a bearing for said U shaped member, said retaining rod where its outer end is pivotally connected to the outer end of the bent over portion of the torque arm adapted to act as a stop member to prevent lateral displacement of said U shaped member, a twisting shaft having means at its lower end for holding the other end of said swab, said twisting shaft passing transversely with respect to said bent over portion of said torque arm through

both legs of said U shaped member to prevent vertical displacement of said U shaped member, said U shaped member also acting as a bearing surface for said twisting shaft, a ratchet plate attached to one face of said U shaped member, said ratchet plate having an opening with inwardly directed ratchet projections and a pawl attached to said twisting shaft for engaging the projection on said ratchet plate. 5

2. In a wringer mop, a compensating spring 10 actuated torque arm construction comprising an elongated handle, a torque arm pivoted transversely to said handle to swing toward and away from said handle, a push rod pivotally connected at its outer end to the outer end of said torque arm, and at its inner end slidably and pivotally mounted to said elongated handle at a point offset from the pivot point of said torque arm, and a compression spring mounted on said push rod for springing the wringer mop to and retaining 20 it in wringing position.

3. In a wringer mop, a torque arm construction comprising an elongated handle, a torque arm pivoted transversely to said handle to swing toward and away from said handle and a spring 25 attached to said torque arm at one end and to the handle at its other end for springing the wringer mop to and retaining it in wringing position.

4. In a wringer mop, a compensating spring 30 actuated torque arm construction comprising an elongated handle, a torque arm pivoted transversely to said handle to swing toward and away from said handle, a center pin pivotally mounted in said handle at a point offset from the pivot 35 point of said torque arm, a push rod slidably mounted through said center pin, and pivotally connected at its outer end to the outer end of said torque arm, said push rod having a stop portion, and a spring mounted on said rod and 40 compressible between said center pin and said stop portion for springing the wringer mop to and retaining it in wringing position.

5. In a wringer mop, a torque arm construction for retaining the wringer mop in wringing 45 position, comprising an elongated handle, a torque arm pivoted transversely to said handle to swing toward and away from said handle, and a retaining rod pivotally connected at its outer end to the outer end of said torque arm and at its 50 inner end slidably and pivotally mounted to said handle at a point offset from the pivot point of said torque arm.

6. In a wringer mop, a wringing mechanism for twisting a swab, comprising a U shaped bearing, a twisting shaft passing through both legs of said U shaped bearing, a ratchet plate mounted on one face of said U shaped bearing, said ratchet plate having an opening with inwardly directed ratchet projections, a casing secured 60 against rotation on said twisting shaft, a pawl pivotally mounted within said casing to rotate with said twisting shaft and passing through the lower end of said casing for engagement with the projections on said ratchet plate, a selector 65 slidably mounted between said twisting shaft and said pawl within said casing and a spring mounted on one side of the selector for actuating said pawl so that as the selector is moved and the end of said spring passes the pivot point of the pawl, 70 engagement or disengagement of the pawl on the projections of the ratchet plate takes place.

7. In a wringer mop, a wringing mechanism for twisting a swab, comprising a U shaped bearing, a twisting shaft passing through both legs of 75

5 said U shaped bearing, a ratchet plate mounted on one face of said U shaped bearing, said ratchet plate having an opening with inwardly directed ratchet projections, a casing secured against rotation on said twisting shaft, a pawl pivotally mounted within said casing to rotate with said twisting shaft and passing through the lower end 10 of said casing for engagement with the projections on said ratchet plate, a selector slidably mounted between said twisting shaft and said pawl within said casing and a spring mounted on one side of the selector for actuating said pawl so that as the selector is moved and the end of said spring passes the pivot point of the 15 pawl, engagement or disengagement of the pawl on the projections of the ratchet plate takes place, and a stop member mounted on said shaft below said U shaped bearing for retaining the U shaped bearing against the ratchet plate and the 20 ratchet plate in turn against the casing.

8. In a wringer mop, a wringing mechanism for twisting a swab comprising a twisting shaft, a ratchet mechanism for holding the twisting shaft at certain stages of the wringing operation, said ratchet mechanism having a reciprocating, revolving pawl mounted to rotate with said twisting shaft, and a ratchet plate having a plurality of recesses for engagement by said pawl, said twisting shaft passing through an opening in said ratchet plate and a manually operable selector 10 non-rotatably and slidably mounted on the twisting shaft, and a spring fixed to said selector so that upon a longitudinal movement of said selector and upon pressure then being applied to the twisting shaft in the same directional movement 15 of the wringing operation said spring pushes said pawl out of engagement with the recesses of said ratchet plate and the twisting shaft is released from a held position.

JOHN L. NILSON. 20
